UNITED STATES PATENT OFFICE

150,530

DESIGN FOR AN EXPANSIBLE WATCH BRACELET

Arthur Albanese, Providence, R. I., assignor to Marvel Jewelry Mfg. Company, Providence,
R. I., a corporation of Rhode Island

Application December 3, 1947, Serial No. 142,933

Term of patent 14 years

(Cl. D45—4)

To all whom it may concern:

Be it known that Arthur Albanese, a citizen of the United States, residing at Providence, in the county of Providence and State of Rhode Island, has invented a new, original, and ornamental Design for Expansible Watch Bracelet, of which the following is a specification, reference being had to the accompanying drawing, forming part thereof, wherein:

I claim:

The ornamental design for an expansible watch bracelet, as shown and described.

ARTHUR ALBANESE.
